UNITED STATES PATENT OFFICE.

HERMAN KAPOLKIN, OF NEW YORK, N. Y.

CONCRETE RAILROAD-TIE.

1,384,070.

Specification of Letters Patent. Patented July 12, 1921.

Application filed July 17, 1920. Serial No. 396,912.

To all whom it may concern:

Be it known that I, HERMAN KAPOLKIN, a citizen of the United States, and a resident of the city of New York, borough of 5 Manhattan, in the county and State of New York, have invented new and useful Improvements in Concrete Railroad-Ties, of which the following is a full, clear, and exact description.

10 Among the principal objects which the present invention has in view are: To increase the permanency of railroad constructions; to decrease the need of repair of railroad beds; to strengthen the road bed construction; to facilitate the upkeep of the bed; to prevent the loosening of the rails; and to assist in retaining a train on the road bed in the event of derailment.

15

Drawings.

20 Figure 1 is a cross section taken as on the line 1—1 in Fig. 2, of a railroad tie of usual construction, showing in conjunction therewith, a fragment of a concrete tie, and metal reinforce therefor.

25 Fig. 2 is a plan view showing a fragment of the rail and the metal reinforce used in forming the railroad tie, the concrete with which the said tie is associated, being removed.

30 Fig. 3 is a plan view on reduced scale showing a fragment of a railroad rail and of completed concrete tie therefor, together with means for mounting said rail on said tie, a portion of the concrete being broken away to show the arrangement of the reinforce employed therewith.

35 Fig. 4 is a cross section, the section being taken as on the line 4—4 in Fig. 3, the concrete structure being indicated by the broken lines.

40 Fig. 5 is a detailed view on enlarged scale showing the method employed for preventing the loosening of nuts on bolts used in the construction of the road bed.

45 Fig. 6 is a detailed view in perspective showing a foot for holding the rail in position.

50 Fig. 7 is an end view of a tie constructed in accordance with the present invention and showing in conjunction therewith, a fragment of railroad rail.

Description.

55 As shown in the drawings, the tie has been constructed in accordance with the present invention having a concrete body 12 which

is cast and allowed to set around longitudinal metal reinforce tie rods 13. The rods 13 as seen best in Figs. 2 and 3 of the drawings are disposed in parallel relation and are held from spreading apart by U-couples 14. Preferably the ties 13 and the couples 14 are constructed from tubing. The tubing from which the couples 14 are constructed particularly facilitates the threading of the up-turned ends thereof to form the tapped sockets 15 which extend vertically to receive the bolts 16.

60 The bolts 16 as seen in Fig. 1 of the drawings are threaded and have each a head 17 which bears upon a foot plate 18 in service.

65 The body 12 is cast to provide a series of cross ribs 19 which are disposed between the rails 20 in service and are intended to form 70 guide grooves to hold the wheels of an engine or car on the road bed if the engine or car jumps the rails 20.

75 At the opposite ends and between the up-turned sections of the couples 14 are provided sockets or seats for heavy wooden bolsters 21. The bolsters 21 are surmounted by metal plates 22 on which the rails 20 rest. The plates 22 protect the bolsters 21 from the wear incident to the vibration of 80 the rails 20.

85 The plates 22 are held in place by the bolts 16, perforations being provided in the said plates through which are extended the bolts 16. In service the plates 22 are spaced 90 from the ends of the couples 14 as shown best in Fig. 1 of the drawings. By this means the vibration imparted by a passing train to the plates 22 is prevented from being transmitted to the body 12 of the railroad tie. The vibration or shock of the passing train is absorbed by the bolsters 21.

95 When building a road bed wherein ties constructed and arranged as in accordance with the present invention are being used, 100 the ties are placed in a manner similar to that at present employed. The bolsters 21 and plates 22 are then placed in position to receive the rails 20.

105 When the rails 20 have been laid, the foot plates 18 are adjusted on the bolts 16 and these latter are introduced through the perforations provided in the plates 22 and are screwed into the tapped sockets formed in the upturned ends of the couples 14. Before tightening the foot plates 18 on the flanges of the rails 20, the ties are accurately disposed as is done in railroad construction. The ties having been placed, the bolts 16 are 110

tightened with the result that the foot plates 18 are pressed firmly upon the flanges of the rails, forcing the same rigidly upon the plates 22.

5 To lock the bolts 16 in position, the keys 23 are driven home in the grooves 24 provided in the foot plates 18. The keys 23 are preferably constructed of wrought metal and are provided with upturned ends 25
10 which are driven against one side of the bolt head 17, as seen best in Fig. 5 of the drawings. The keys pass under the bolt heads 17, which it will be understood are not otherwise prepared for the said keys. The free
15 ends of the keys 23 are then upset to prevent their becoming loose in the grooves 24, with the possibility that they may escape therefrom.

It is obvious that while the keys 23 form
20 an efficient lock for the bolts 16, they may readily be removed from service so that the bolts may be tightened or loosened as the exigencies of the case demand. The operation of loosening consists, first in striking
25 down the free ends of the keys 23 and then driving them backward through the grooves 24 until the heads 25 free the heads 17.

It will be seen best in Fig. 1 of the drawings that the body of the plates is so
30 constructed that when the overhang 26 thereof bears firmly on the flange of the rail 20, the said body is slightly removed from the plates 22. Thus allowing for tightening of the plates 18 on the flanges of the
35 rail.

After the rails have been set, ballast of broken stone or other materials is placed on the bed and tamped under and beside the ties 12. To facilitate this operation the
40 body 12 of the ties is provided with inclined surfaces 27 converging to a dependent ridge as shown best in Fig. 7 of the drawings. The wedge-shaped space naturally formed under each tie by reason of this construction
45 forms a pocket for the loose stones or particles of the ballast and facilitates the tamping which is provided to drive the ballast below the said tie. Also during the service life of the ties it becomes necessary from
50 time to time to steady the ties. The tamping incident thereto is readily and quickly performed by reason of the formation of the bottom of the said ties.

Claims.

55

1. A railway tie comprising a body portion constructed from plastic setting material; a metal reinforce therefor, embodying longitudinally disposed tie rods and positioning couples therefor, said couples forming operatively opening sockets; a plurality of yielding bolsters mounted on said body between the ends of said couples; a plurality of rigid wearing plates mounted on said bolsters; fastening means for holding said wear plates in position, said means engaging said couples; and a plurality of foot plates, each engaging one of said fastening members to be drawn upon the flange of a railway rail in service. 70

2. A railway tie comprising a body portion constructed from plastic setting material; a metal reinforce therefor, embodying longitudinally disposed tie rods and positioning couples therefor, said couples forming operatively opening sockets; a plurality of yielding bolsters mounted on said body between the ends of said couples; a plurality of rigid wearing plates mounted on said bolsters; a plurality of screw bolts operatively engaging said plates, and tapped sockets in said couples; a plurality of foot plates each operatively engaging one of said bolts; a plurality of keys each adapted for interposition between said foot plates and the head of said bolt, said keys being adapted for engaging said bolts to prevent the rotation thereof; and means for holding said keys on said foot plates. 80

3. A railway tie comprising a body composed of plastic setting material; a metal reinforce therefor, embodying a plurality of tie rods disposed in relation lengthwise of said body and in approximately parallel relation; a plurality of U-shaped couples enfolding said tie rods, each of said couples having an upwardly opening screw threaded socket; a plurality of wooden bolsters mounted in said body portion between said U-shaped couples in guided relation thereto for supporting lateral strains thereon; a plurality of metal wear plates mounted on said bolsters; and a plurality of fastening members for engaging said wear plates and said couples. 90
